UNITED STATES PATENT OFFICE.

JOHN KARHU, OF CALUMET, MICHIGAN, ASSIGNOR OF ONE-HALF TO RICHARD T. LOONEY, OF HANCOCK, MICHIGAN.

DUMPING-CAR.

1,095,879.

Specification of Letters Patent.

Patented May 5, 1914.

Application filed April 3, 1913. Serial No. 758,628.

To all whom it may concern:

Be it known that I, JOHN KARHU, a citizen of the United States, residing at Calumet, in the county of Houghton and State of Michigan, have invented certain new and useful Improvements in Dumping-Cars; and I do declare the following to be a full, clear, and exact description of the invention, such as will enable others skilled in the art to which it appertains to make and use the same.

This invention relates to railway rolling stock, and more especially to laterally tilting dumping cars; and the object of the same is 15 to effect certain improvements over my former Patent Number 1,046,602, dated December 10, 1912.

With this object in view the invention consists in certain details more fully described 20 hereinafter and brought out in the claims, and the same are illustrated in the accompanying drawings wherein—

Figures 1 and 2 are end elevations of a car embodying my improvements, the 25 former showing the body as upright and the latter view showing it as dumped. Fig. 3 is an enlarged end elevation of one corner of the car, and one of the hinges; and Fig. 4 is a sectional view on the line 4—4 of Fig. 3. 30 Fig. 5 is a plan view of this corner of the car, partly in section; and Fig. 6 a perspective detail of the hinge member thereof. Fig. 7 is a perspective detail of the bolt detached from said hinge member; and Fig. 8 35 is a perspective detail of the lever for throwing said bolt. Fig. 9 is a horizontal section through the pivot of the arm, the eye at the inner end of the locking bolt, and the eccentric cam at the inner end of the hand 40 lever. Fig. 10 is an enlarged horizontal section of the same part in a slightly modified form, and Fig. 11 is an elevation of such part with the head of the pivot bolt removed. Fig. 12 is a similar elevation with 45 the lever lock standing in a different position. Fig. 13 is an elevation of the eye at the inner end of the arm. Fig. 14 is a perspective detail of the lock proper.

The car truck T is mounted on wheels W 50 and carries a central longitudinal bar L, to which at H is hinged the car body B having fixed ends E and movable sides S. The construction may follow that disclosed in my prior patent, or that of ordinary coal or ore 55 cars commonly employed and which dump

to either side, and the details, proportions, and materials of parts are not essential to the present invention.

At C, C are illustrated catches carried by the body B, and one of them engages one of 60 the keepers K carried on the truck as set forth in my prior patent.

No novelty is claimed for the parts thus far described.

When the car body B stands horizontal, as 65 seen in Fig. 1, the sides rest against the beveled extremities e of the ends E, and the parts may be held in this position by chains as illustrated in Fig. 1 if desired, and especially if the car is to be subjected to rather 70 rough usage. But it is the purpose of the present invention to provide means for locking the sides and their supporting elements in this position so that the chains may be omitted. When the body is tilted to the position shown in Fig. 2 it is held there by means of one of the catches engaging a keeper as set forth in my prior patent, but as the material within the car soon runs out of its body when the latter is thus tilted, the 75 catch serves the purpose only of holding it against accidental righting.

Coming now to the details of the present invention, each side board is rigidly mounted at the outer end of a sector-shaped casting constructed as best seen in Fig. 6, and as the means for connecting the side boards S thereto are unimportant, I designate them broadly herein by the numeral 1. Such fastening device 1 is carried by an upright 85 plate 2 which is cast over the outer edge of an arc 3, and in a brace between the plate and arc is disposed a pin or stud 4 to which one of the chains 5 may be hooked if desired. The arc is supported by two arms 6 and 7 90 which converge toward and merge into a hub having an eye 8 disposed at the center of said arc, and this eye is pivotally mounted on a bolt 10 which is fixed through the car end E—a bushing 9 being by preference 100 interposed between the bolt and the inner wall of the eye 8. The angle of the plate 2 (and therefore of the side board S) to the upper end of the arc 3, and its disposition with reference to the pivot bolt 10 is such 105 that as the side board starts upward from the position shown in Figs. 1 and 3 it moves slightly away from the beveled end e of the end board E, and finally reaches the position shown at the right of Fig. 2. 110

In Fig. 7 is shown a bolt 11 having at its inner end an eye 12, its body along its outer side being provided with a stop 13 and the eye with another stop 14, the outer side of 5 said body having a longitudinal rib 15, its outer end having a lug 16 with a downwardly facing shoulder 17, and the outer extremity of said body forming the tip 19 of the bolt, said tip being adapted to travel 10 in a groove 20 in the radial inner face of the arc 3 of the casting shown in Fig. 6. Pivoted at 21 to the lug 16 is a rod 22 whose lower end is pivoted at 23 on the truck T; and the length of the two rods is such that 15 when the body B is level the parts stand as seen in Fig. 1, but when the body is tilted one rod draws downward on one bolt while the other rod pushes upward on the other bolt as seen in Fig. 2. The length of the 20 groove 20 is such that the left hand bolt in Fig. 2 may be drawn downward within its arc 3 as shown, but in tilting the body to the right as shown in that view it is obvious that the right hand rod 22 will raise the 25 right hand bolt 11 so that the right hand casting and side board S will be elevated and the car body dumped at that side. This follows from the fact that when the body stands horizontal the tips 19 of the two 30 bolts rest in the respective grooves 20 a slight distance beneath the inturned upper ends 2' of the plates 2 whereby a lost motion is permitted and either plate-extension 2' may move downward a trifle before it strikes the 35 tip 19 of its bolt. With the latter projected as seen in Fig. 5 (by means yet to be described) the shoulder 17 of the lug 16 stands above a shoulder 3' formed in one wall of the groove 20 as seen in Fig. 6; and with 40 these shoulders in contact as seen in Fig. 3, the lost motion just described is not permitted because, although there is nothing to prevent the remote side of the body moving downward, the contacting shoulders prevent 45 either side of the body from moving upward. It follows therefore that if one bolt be retracted by any means, so that its shoulder 17 disengages the shoulder 3' in the runway or guide 20, that side of the body may 50 ascend as seen in Fig. 3 and the other side will of course descend to dump the car. If both bolts should be retracted the car may be dumped to either side. The push rods 22 swing the bolts 11 as the car dumps, one 55 bolt moving downward freely in the groove 20 and the other moving upward and carrying the casting with it.

In Fig. 8 is shown a lever 40 having on the inner side of its inner end a cam 41 pierced 60 eccentrically with an eye 42 through which passes the main bolt 10, and the cam 41 is of a size to fit loosely within the eye 12 of the locking bolt 11. One side of the wall of this eye 12 is illustrated in Fig. 7 as having 65 a socket or pocket 43 in which is a coiled

expansive spring 44 pressing the heel end 45 of the lever 40 normally outward so that its body 40 and its handle end 46 are thrown normally inward, and if the back or inner side of said body is grooved longitudinally 70 as shown at 47, this groove is thrown into normal engagement with the rib 15 on the bolt 11. The stops 13 and 14 above described, and well shown in Fig. 7, limit the throw of the lever 40 from one position as 75 seen in Fig. 5 over to the opposite position as seen in Figs. 2 and 3. In its movement, it swings around the axis of the main bolt 10, and the cam face 41 engaging the eye 12 of the locking bolt 11 causes the latter to be 80 projected or retracted in a manner which will be clear. When projected the shoulder 17 engages the shoulder 3' in a manner above described, and the dumping of the car in at least one direction is prohibited; when retracted these shoulders 85 come out of engaged position and the car may be dumped as already explained. An assembly of the cam, the eye 12, and the main bolt 10 is well illustrated in Fig. 9. 90 With this construction, when it is desired to dump the car it is obviously necessary for the operator to move the lever 40 on that side which will be the high side of the car, or move two such levers if this locking device is duplicated at the opposite end of the 95 car shown in Figs. 1 and 2. Next he must of course unlatch at least one of the chains 5, or both chains if they are employed at both ends of the car. Then the latter may 100 be dumped as seen in Fig. 2, and in the act of dumping the tip 19 of the locking bolt at the right side of the car travels upward in the groove 20 and strikes the plate-extension 2' so that the right hand side S is raised as 105 will be clear. When the parts are restored to a horizontal position the tip 19 of the left hand locking bolt travels upward whereas the right hand side S moves downward until it rests in place and then the tip 110 19 of this locking bolt moves downward; when both tips come into proper position the right hand shoulders 17 and 3' engage and at this time the left hand lever can be swung back to its position against the stop 13 so 115 as to project the left hand bolt 11 with its shoulder in engagement with the left hand shoulder 3'. Thus the car body is locked against dumping in either direction. It is quite obvious that if this mechanism is duplicated at the opposite end of a car, the proper bolt 11 must be retracted at that end also, and after dumping the proper bolt 120 should be reset.

An amplification of my invention is illustrated on Sheet 3 of the drawings, and this consists in means for locking the lever 40 when it has been thrown to position to project the bolt 11 which, as above described, locks the car against dumping. While it is 125 130

improbable it is yet possible that vibration might throw one of the levers 40 from its position where the parts are locked, over onto the opposite stop 14 where the parts are 5 unlocked, with the result that the car could and possibly would dump automatically and undesirably. Also it is obvious that the lever could be so thrown by a person who was maliciously inclined. Hence the provision of a lever-lock now to be described. The use of the spring 44 and the rib 15 engaging the groove 47 of the lever 40 holds the latter in active position only by friction. I might duplicate this arrangement in connection with the lever lock below, although I have shown on Sheet 3 of the drawing another form of tension spring for holding the rib engaged with the groove. It is even possible that the spring, the rib, and the 10 groove could be entirely omitted when the lever lock is employed. Journaled through the cam or eccentric 41, parallel with the main bolt 10, is a rock shaft 50 which in the present instance is illustrated as having a 15 triangular front end 51 adapted to be engaged by a peculiar shaped key, and projecting radially from the body of said shaft is a tumbler 52 adapted to be housed within a recess 53 in the cam when the shaft 50 is 20 turned in one direction, or adapted to be thrown outward into engagement with a recess 54 in the inner wall of the eye 12 of the locking bolt if the shaft 50 be turned in the opposite direction—here the left. 25 The shaft has flattened sides 56 engaged by a spring 57 to hold it yieldingly in various positions. Assuming now that this lever lock is set as last described, if a miscreant should endeavor to throw the lever 40 he 30 grasps the handle end 46 and seeks to lift it, and immediately the outer end of the tumbler 52 strikes the flat upper end of the recess 54 and he finds that the lever cannot be moved. Having no key which will engage the front end 51 of the rock shaft 50, he 35 cannot unlock the device and therefore he cannot throw the lever. On the other hand, when it is desired to dump the car, a person in authority having the proper key can turn 40 the rock shaft and in so doing he throws the tumbler out of engagement with the recess 54 and houses it within the recess 53 within the cam, after which he may throw the lever and the cam turns in the eye 12 and carries 45 the tumbler with it. I give this explanation and illustration as typical only of one form of lever lock which may well be employed in this connection, but do not wish to be limited thereto. Sheet 3 of the drawings 50 also shows how the coiled expansive spring 44 located within the pocket 43 may be replaced by a coiled expansive spring 64 surrounding the main bolt 10 under its head 10' and located within a pocket 63 formed 55 in the outer face of the cam; and if this con-

struction be adopted it is clear that before the lever 40 can be thrown it will have to be bodily drawn outward on the main bolt so that its groove 47 will disengage the rib 15, whereas with the construction shown in 70 Figs. 7 and 8 the lever 40 need be sprung outward at its handle end only and for a distance sufficient to disengage said groove from the rib. As above suggested, this detail also is unimportant, and either described form or any equivalent form may be employed. In fact, in the simpler and cheaper types of this device it might be possible to entirely omit the lever lock and either form of spring 44 or 64, as well as 75 the groove and rib constituting the latching means for holding the lever frictionally in active position, and rely on the weight of said lever to remain upon the stop 13. 80 The important feature of the present improvement over my prior patent is the provision of a locking bolt 11 having a shoulder 17 adapted to engage a shoulder 3' in the runway or groove 20 when said bolt is projected, such engagement preventing the elevation of this side of the car body B; therefore the car cannot be dumped to the opposite side, although it is yet possible to dump it on this side. The fact that the distance between said shoulder 3' and the overhanging plate 2' is greater than the height of the bolt tip 19, gives a certain degree of lost motion which may be useful if the parts are made of rough castings and do not fit each other accurately. In the act of dumping 90 the car this lost motion occurs while the side being dumped is descending slightly, and therefore the side board S does not start upward relatively to this side immediately the latter begins to descend. The 95 result is that some of the ore, coal, or other material with which the car is loaded falls against or starts toward this side board, and when the latter rises the load dumps with a rush and its travel toward that side 100 of the car automatically assists in the act of dumping the latter completely. 105

What is claimed as new is:

1. In a laterally dumping car, the combination with the body pivotally supported on the truck, upwardly movable sides, and castings supporting each side and pivotally connected with the ends of the body, each casting having a groove around its pivot and a shoulder in one wall of the groove; of a locking bolt movably mounted at its inner end on the pivot of each casting and having its tip movable in said groove, a shoulder on the bolt adapted to be engaged with that in the wall of the groove when the bolt is projected, and a push rod connecting the truck with the bolt near its outer end. 115 120 125

2. In a laterally dumping car, the combination with the body pivotally supported on the truck, upwardly movable sides, and 130

castings supporting each side and pivotally connected with the ends of the body, each casting having a groove around its pivot and a shoulder in one wall of the groove; of a 5 plate closing the upper end of said groove and disposed some distance from the shoulder in its wall, a locking bolt having its inner end movably mounted on the pivot of the casting, its tip movable in said groove, and a 10 lug on its body provided with a shoulder adapted to be engaged with that in the groove-wall when the bolt is projected, the same having some lost motion between the groove-shoulder and said plate, and a push 15 rod connecting the truck with the bolt near its outer end.

3. In a laterally dumping car, the combination with the body pivotally supported on the truck, upwardly movable sides, and 20 castings supporting each side and pivotally connected with the ends of the body, each casting having a groove around its pivot and a shoulder in one wall of the groove; of a lever having an eccentric cam at its inner 25 end pivotally mounted on the pivot of said casting, a locking bolt having an eye at its inner end loosely embracing said cam and a tip at its outer end mounted in the groove of the casting, a lug on said bolt near its outer 30 end provided with a shoulder adapted to engage that in the wall of said groove when the lever is projected, and a push rod pivotally connecting said lug with the truck.

4. In a laterally dumping car, the combination with the body pivotally supported on the truck, upwardly movable sides, and castings supporting each side and pivotally connected with the ends of the body, each casting having a groove around its pivot and a 40 shoulder in one wall of the groove; of a lever having an eccentric cam at its inner end pivotally mounted on the pivot of said casting, a bolt having an eye loosely surrounding said cam and a pocket at one side 45 of its eye, an expansive spring within said pocket bearing against the heel of the lever, the body of the latter being grooved on its under side, a rib on the bolt normally engaging said groove, the tip of said bolt movable in the groove of the casting, a shoulder 50 on the bolt adapted to engage that in the groove-wall when the bolt is projected, and a push rod connecting said bolt with the truck.

5. In a laterally dumping car, the combination with the body pivotally supported on the truck, upwardly movable sides, and castings supporting each side and pivotally connected with the ends of the body, each 60 casting having a groove around its pivot and a shoulder in one wall of the groove; of a lever having an eccentric cam at its inner end pivotally mounted on the pivot of said casting, a bolt having an eye loosely surrounding said cam and a pocket at one side 65

of said opening, an expansive spring within said pocket bearing against the heel of the lever, the body of the latter being grooved on its under side, a rib on the bolt normally engaging said groove, a stop projecting from the bolt beneath said rib and a second stop projecting from its eye for the purpose set forth, the tip of the bolt movably engaging the groove in said casting, a shoulder thereon adapted to engage that in the groove-wall when the bolt is projected, and means for moving the bolt in the groove when said shoulders are disengaged. 70

6. In a laterally dumping car, the combination with the body pivotally supported on the truck, upwardly movable sides, and castings supporting each side and pivotally connected with the ends of the body, each casting having a groove around its pivot and a shoulder in one wall of the groove; of a lever having an eccentric cam at its inner end pivotally mounted on the pivot of said casting, and having its under side grooved, a bolt having an eye loosely surrounding said cam, a rib on the bolt normally engaging said groove, a spring pressing the lever normally toward said bolt to engage said groove and rib when the lever overlies the bolt, a stop projecting from the bolt beneath said rib and a second stop projecting from its eye for the purpose set forth, the tip of the bolt movably engaging the groove in said casting, a shoulder thereon adapted to engage that in the groove-wall when the bolt is projected, and means for moving the bolt in the groove when said shoulders are disengaged. 80

7. In a dumping car, the combination with the truck, the body pivoted thereon and having fixed ends and movable sides, and castings supporting each of the sides and pivoted at their inner ends to the ends of the body, each casting having a groove curved around its pivot and provided with a shoulder in one wall; of a bolt having an eye at its inner end loosely surrounding the pivot for the casting and a lug near its outer end provided with a shoulder adapted to engage that in the casting when the bolt is projected, a push rod connecting said bolt with the car truck, an eccentric cam rotatably mounted in said eye and pivotally mounted on the pivot for said casting, and means for turning this cam in either direction for the purpose set forth. 90

8. In a dumping car, the combination with the truck, the body pivoted thereon and having fixed ends and movable sides, and castings supporting each of the sides and pivoted at their inner ends to the ends of the body, each casting having a groove curved around its pivot and provided with a shoulder in one wall; of a bolt having an eye at its inner end loosely surrounding the pivot for the casting and a lug near its 100

- outer end provided with a shoulder adapted to engage that in the casting when the bolt is projected, a push rod connecting said bolt with the car truck, an eccentric cam 5 rotatably mounted in said eye and pivotally mounted on the pivot for said casting, a lever for turning this cam in either direction for the purpose set forth, and means for locking said lever when the bolt is projected.
10. In a dumping car, the combination with the truck, the body pivoted thereon and having fixed ends and movable sides, and castings supporting each of the sides 15 and pivoted at their inner ends to the body, each casting having a groove curved around its pivot and provided with a shoulder in one wall; of a bolt having an eye at its inner end loosely surrounding the pivot for 20 the casting and a lug near its outer end provided with a shoulder adapted to engage that in the casting when the bolt is projected, a push rod connecting said bolt with the car truck, an eccentric cam 25 rotatably mounted in said eye and pivotally mounted on the pivot for said casting, a lever projecting radially from said cam and lying alongside the bolt when the latter is projected, and means for locking the cam to 30 the bolt at this time.
10. In a dumping car, the combination with the truck, the body pivoted thereon and having fixed ends and movable sides, and castings supporting each of the sides 35 and pivoted at their inner ends to the body, each casting having a groove curved around its pivot and provided with a shoulder in one wall; of a bolt having an eye at its inner end loosely surrounding the pivot for 40 the casting and a lug near its outer end pro-
- vided with a shoulder adapted to engage that in the casting when the bolt is projected, a push rod connecting said bolt with the car truck, an eccentric cam rotatably mounted in said eye and pivotally mounted 45 on the pivot for said casting, a lever projecting radially from said cam and lying alongside the bolt when the latter is projected, the lever having a groove and the bolt having a rib adapted to engage the 50 same at this time, yielding means throwing the lever toward the bolt, and means for locking them in this position.
11. In a dumping car, the combination with the truck, the body pivoted thereon 55 and having fixed ends and movable sides, and castings supporting each of the sides and pivoted at their inner ends to the ends of the body, each casting having a groove curved around its pivot and provided with 60 a shoulder in one wall; of a bolt having an eye at its inner end loosely surrounding the pivot for the casting and a lug near its outer end provided with a shoulder adapted to engage the shoulder in the casting 65 when the bolt is projected, connections between said lug and the car truck, an eccentric cam rotatably mounted in said eye and pivotally mounted on the pivot for said casting, and a lever projecting radially from 70 said cam and lying alongside the bolt when the latter is projected, for the purpose set forth.

In testimony whereof I have hereunto set my hand in presence of two subscribing 75 witnesses.

JOHN KARHU.
